UNITED STATES PATENT OFFICE.

THOMAS F. HEMMICK, OF READING, PENNSYLVANIA.

PUDDLING AND HEATING FURNACE.

SPECIFICATION forming part of Letters Patent No. 371,454, dated October 11, 1887.

Application filed December 15, 1886. Serial No. 221,001. (No model.)

To all whom it may concern:

Be it known that I, THOMAS F. HEMMICK, a citizen of the United States, residing at the city of Reading, county of Berks, State of Pennsylvania, have invented a new and useful Improvement in Puddling and Heating Furnaces, of which the following is a specification.

This improvement is more particularly related to a device for consuming the unignited products of combustion passed off of the coal upon the fire-grate, in combination with certain defined changes in the construction of the bridge-wall and roof of the furnace.

15 The object of the improvement is to give to the puddler or heater a better control of the flame in operating the furnace, whereby the process is more rapidly completed, and to secure more comfort to the operator, as the device, properly controlled, does not throw the flame out of the door when the same is opened to withdraw or replenish the charge in the same, and to do away with the production of smoke in operating the same with soft coals.

20 The drawings herewith fully detailed show the nature of my improvement, like letters of reference indicating like parts throughout.

Figure 1 is a sectional elevation of a puddling-furnace with my improvements attached.

25 Fig. 2 represents an end elevation of the fire-grate end of the furnace with the blast-pipe in place. Fig. 3 represents the same end elevation, with the blast-pipe removed, showing the sleeve and tuyere-box and valve in place; Fig.

30 4, a front elevation of the sleeve or receiving-box; Fig. 5, a top plan of the same; Fig. 6, a cross-section on the line *a a* of the same. Fig. 7 represents in front elevation the tuyere-box of the gas consumer; Fig. 8, a top plan of the same; Fig. 9, a cross section on the line *b b* of

35 the same. Fig. 10 represents in plan the upper face of the tuyere-lip or regulating-valve and a section on the line *c c*. Fig. 11 represents in plan the under or lower face of the tuyere-lip or regulating-valve, with a section on the line *d d*. Fig. 12 represents in front elevation the cap of the tuyere-box with the blast-nozzle opening in the same; Fig. 13, an end elevation of the same. Fig. 14 represents,

40 upon an enlarged scale and in section, the operation of the lip or regulating-valve, showing

ing the same opened to its maximum extent, uncovering the opening in the tuyere-nose. Fig. 15 represents the same arrangement, showing the lip or regulating-valve closed over the tuyere-nose.

55 In all the drawings, A represents the girders supporting the furnace-bed B, upon which is placed the bed C, or, in lieu of same, water-chills.

60 D represents the neck of the furnace; E, the roof of the same; F, the end wall; G, fire-bridge wall; H, end plates; I, ash-pit doors; J, bed-plate; K, grate-bars; L, stock-hole; M, working door; N, ash-pit; P, coal upon the grates.

65 With some exceptions, hereinafter noted, the above are the usual salient points in furnace construction, and I make no claim to the same.

70 My improvement consists in the following points:

75 First. Terminating the ordinary fire-bridge wall from three to four courses of fire-brick below its destined top level, and capping the same with three or four courses of fire-brick, 1, 2, and 3, each course projecting from one to one and one-half inch or more over the plumb-line of the bridge-wall and of each other toward the combustion-chamber until the proper elevation of the bridge-wall is attained. 80 Preferably equivalent integral brick shapes will be used for the above purpose.

Second. In constructing the roof of the furnace I place transversely across the same, about on a line or near to the opening for the working-door on the side next to the fire-bridge wall, three or four longitudinal courses of brick, 4, 5 and 6, so arranged as to length that each course shall successively drop from 90 one to one and one half inch below the level of the roof-bricks and of each other, thus forming the greatest drop or obstruction near to the door-line, as shown in section, Fig. 1, and for this purpose preference will be given to 95 integral brick shapes.

Third. At the combustion or fire-pot end of the furnace I introduce a sleeve or open receiving-box, 7, with flanges 8 and fulcrum-post 9, supporting the same upon and within a suitable opening, H', cut equally out of the two upper end plates, as shown in Fig. 3. In

the rear of said sleeve two courses of fire-brick shapes, 10 and 11, are built across the furnace, near to the roof of the same—the course 11 in line with the lower edge of the opening in the sleeve, and the course 10 so arranged by a slight arching for their support as to form an opening or slot, 12, next to the fire-pot for the discharge of air from the blast-pipe 29 into the combustion-chamber.

10 Fourth. A tuyere or valve box, 13, with flanges 14 and nose 15, is adapted to slip from the outside within the projected portion of the sleeve 7, and is provided with a lip or valve, 16, to the nose 15 of the same, the lip or valve being pivoted to three links, 17, by ears 18, and to the sides and partition 31 of the tuyere-nose by pivots 19 through the opposite ends of the links. A car, 20, at the upper outer face of the valve 16, is connected with a link, 21, and lever 22 by pivot 23 and fulcrum-pin 24 in fulcrum-post jaw 25. This lever 22 is extended from the fulcrum-post to the working side of the furnace in any convenient manner, and is held in adjustment by dropping 25 the lever into the serrations of an ordinary quadrant-ratchet, which gives the operator complete control of the movement of valve or lip 16, and consequently of the quantity of air passing from the blast-pipe 29, connected by 30 a projected nozzle, 28, of the cap 27, which is secured in a suitable manner to the front of the tuyere-box 13. The air passes through the nose-piece 15 and under the lip 16 out of the slot 12 of the brick-work into the fire-pot 35 or combustion-chamber of the furnace.

15 The projected bricks 1, 2, and 3 of the fire-bridge wall and 4, 5, and 6 of the roof may be burned as integral blocks in suitable thickness for handling, and are preferable for that 40 purpose; but furnaces already in use may be readily adapted to my improvement by using common plain fire-brick, as shown in the sections in Fig. 1, the wedged-shaped pieces 10 and 11 being cut to the form shown.

45 To show the advantages and economy insured by a practical use of my improvement, two furnaces having an identical construction, and which prior to my improvements being introduced used weekly the same average 50 quantity of coal and turned out about the same quantity of iron in equal turns, showed at the end of an eight weeks' trial the following result: The output of iron, as the furnaces were worked on turns, was very nearly the 55 same; but the unaltered furnace required for one week forty-three thousand three hundred and fifty pounds of coal, while the improved furnace did the same work with twenty-seven thousand eight hundred and seventy pounds— 60 a saving of fifteen thousand eight hundred and forty pounds of fuel and a gain of from thirty to forty minutes upon each heat. As they had to wait for their turn, this was a loss; but if all the furnaces in a mill were altered 65 to correspond it would give from four to six heats additional per furnace per day of twenty-four hours, men upon double turn.

The operation of the device is as follows: The fire upon the grate having been urged by the ash-pit blast in the usual way and the 70 bowl of the furnace charged with the requisite amount of material for a heat, the operator, with his eye at a peep-hole in the side of the furnace or through the open door, and having in his hand the end of lever 22, gradually draws down upon the same, which, elevating the lip 16 of the tuyere box 13, permits the blast of air (cold or hot) confined in blast-pipe 29 to pass through the tuyere-box and slot 12 in the wall, the current being so 80 directed by said slot 12 as to strike the fire-bridge wall at about the base of the projected bricks 1, 2, and 3. The current of air thus sent into the combustion-chamber ignites the unburned gaseous products and creates an intense but perfectly clear fire, the flame and heat of which as it rises to clear the bridge-wall is caused by the projected portion of the same to roll over and intimately mix with the entering air, and at the same time, rising to 85 the roof, it meets the projected bricks 4, 5, and 6, or their equivalent, and the heat-wave is deflected downward upon the charge in the bowl of the furnace, which is rapidly heated, and is brought to nature by rabbles in the usual manner. When a fierce heat is desired, the intensity of the blast is increased by reducing the exit-opening in the tuyere-nose, and when it is desired to cool off the furnace the lip or valve is moved to give the 90 maximum opening to the tuyere-nose. Intermediate effects are produced by giving intermediate positions to the lip or valve.

I am aware that locomotive and other fire-boxes have been constructed with the top of the fire bridge overhanging the fire, and that a blast has been introduced above the fire, as well as into the ash-pit under it, and also at other points. I do not claim these features, broadly.

110 What I claim is—

1. In a puddling or heating furnace, the combination of a fire-bridge provided with a projection at the top overhanging the fire, a projection depending from the roof of the furnace 115 behind the bridge, and a slanting aperture in the furnace-wall, through which a blast may be directed to strike the burning gases of the fire immediately below the projecting top of fire-bridge, substantially as and for the purpose set forth.

2. In a puddling or heating furnace, the combination of a fire-bridge provided with a series of courses of fire-bricks, each projecting over the course beneath it and over the fire, a series of courses of fire-brick depending from the roof of the furnace behind the bridge, each successive rearward course depending lower than those toward the bridge, and a slanting aperture in the furnace-wall, through which a blast may be 125 directed to strike the burning gases of the fire immediately below the projecting top of the fire-bridge, substantially as and for the purpose set forth.

3. In a puddling or heating furnace, the combination of a fire-bridge provided with a projection at the top overhanging the fire, a projection depending from the roof of the furnace 5 behind the bridge, a slanting aperture in the furnace-wall, through which a blast may be directed to strike the burning gases of the fire immediately below the projecting top of the fire-bridge, and a blast-receiving box provided 10 with a regulating-valve secured to the outer wall of the furnace, in front of the said aperture, substantially as and for the purpose set forth.
4. In combination with a heating or puddling furnace provided with the blast-aper- 15
- ture 12, the receiving-box 7, secured to the wall in front of the aperture, the tuyere-box 13, slipped within said box and provided with the slanting nose 15, the valve 16, for regulating the passage of the blast through the said 20 nose, the links 17 and 21, supporting said valve, the pivoted lever 22, connected to link 21, for working the valve, and the blast-pipe 29, connected to the tuyere-box, substantially as and for the purpose set forth.

THOMAS F. HEMMICK.

Witnesses:

JAMES R. KENNEY,
HORACE D. BOONE.

It is hereby certified that the name of the patentee in Letters Patent No. 371,454, granted October 11, 1887, for an improvement in "Puddling and Heating Furnaces," was erroneously written and printed "Thomas F. Hemmick;" that said name should have been written and printed *Thomas F. Hemmich*; and that said Letters Patent should be read with this correction therein that the same may conform to the record of the case in the Patent Office.

Signed, countersigned, and sealed this 1st day of November, A. D. 1887.
